Application January 30, 1937, Serial No. 123,233

18 Claims. (Cl. 200—88)

My invention relates to circuit controlling devices in general and more particularly to trip devices for circuit breakers.

An object of my invention is to provide a circuit breaker having an improved trip mechanism capable of opening the breaker after a predetermined time interval in response to an over-load in the controlled circuit, and capable of opening the breaker immediately upon the occurrence of a short circuit condition in the controlled circuit.

Another object of my invention is to provide a trip device for a circuit breaker embodying an improved thermally responsive trip means actuated by a snap-acting disk heated by metallic conduction from a current-carrying heater strip.

Another object of my invention is to provide a circuit breaker embodying an improved thermally responsive trip means which is provided with a simple adjusting means for varying the trip rating of the circuit breaker.

Another object of my invention is to provide an improved thermally responsive trip means for a circuit breaker that is simpler, more efficient and reliable in operation than trip means of the same general type that have heretofore been known or used.

The novel features that I consider characteristic of my invention are set forth in particular in the appended claims. The invention itself, however, both as to structure and operation, together with additional objects and advantages thereof, will best be understood from the following detailed description of a specific embodiment thereof when read in connection with the accompanying drawings, in which:

Figure 1 is a plan view of a multipole circuit breaker embodying the features of my invention, the cover being broken away to illustrate certain details of the breaker;

Fig. 2 is a vertical sectional view of a portion of the circuit breaker illustrated in Fig. 1 taken on the line II—II of Fig. 1;

Fig. 3 is an enlarged central vertical sectional view of the trip device showing the thermally responsive trip means in the normal position;

Fig. 4 is a vertical sectional view of the trip device similar to Fig. 3 showing the thermally responsive trip means in the operative position to effect a tripping operation of the breaker; and

Fig. 5 is a fragmentary view taken on the line V—V of Fig. 3.

Referring to the drawings, the base 1 of the circuit breaker is of molded insulating material

and has mounted thereon the end terminals 3 and 5, the unitary trip structure indicated generally at 7, the circuit breaker operating mechanism 9 which has associated therewith the assembly of the switch members 11 and the arc extinguishers 13 which have integral therewith the main stationary contact 15 and the auxiliary stationary contact 17. The switch members 11 and the stationary contacts 15 and 17 combine to form a plurality of poles. Each of the poles of the circuit breaker is insulated from the adjacent pole by means of one of the insulating barriers 19, which are formed integral with the base 1. These insulating barriers 19 are adapted to align with similar barriers (not shown) in the cover 21, which is likewise of molded insulating material. The operating handle 23, which is rigidly affixed to the switch operating mechanism 9, is also of molded insulating material and has a portion 25 which projects through a suitable opening 27 in the cover 21.

The unitary trip device 7 has a base 29 and a cover 30, both of molded insulating material. The unitary trip structure 7 fits in a suitable recess in the insulating base 1 of the breaker and is fastened therein, as will be described herein-after, through the agency of suitable screw fastenings.

The electric circuit for each of the poles of the breaker is substantially the same. Beginning with the terminal 3, the current passes successively through the arc extinguishing structure 13, the stationary contact 15, the moving contact 31 and the conducting shunt 33 associated with the switch member 11, the unitary trip structure 7—the shunt 33 connecting with the terminal 35 of the trip device—and thence through the trip structure to the other terminal 5.

Each of the switch members 11 has a channel-shaped frame 37 of iron upon which the movable contact is pivotally supported. The moving contact 31 is pivotally fastened to the iron frame 37 by a pivot pin 39 which extends through two openings formed in the opposite sides of the frame 37. Two cotter pins 41 prevent the pivot pin 39 from moving out of position. The flexible shunt 33 is riveted to the moving contact 31 at one end, and at its other end is provided with a terminal portion for engaging the corresponding terminal 35 of the trip structure 7; the screws 47, which engage suitable threaded recesses 49 in the base 1, being provided to releasably connect these terminals.

Each of the moving contacts 31 has a portion 55

51 extending rearwardly into the frame 37. This portion 51 is engaged by the free end of a spring 53; the other end of the spring 53 being rigidly fastened to the frame 37 by means of rivets 55.

5 A square insulating tie-bar 57 extends across all three poles of the breaker. This bar is rigidly affixed to the rearward portion of each of the switch members 11 by means of an iron strap 59 which loops about the bar 57 and has projections (not shown) which extend through suitable openings in the frame 37 and are therein clenched. This bar serves to rigidly connect all of the switch members 11 and thereby makes it possible to operate all three of the switch members from a single operating mechanism. Also, this bar provides a means whereby all the poles of the breaker are opened and closed simultaneously.

20 Any suitable type of arc extinguishing structure may be used. The arc extinguishers shown are of the spaced plate type and are completely described in the application of M. W. Brainard, Serial No. 593,236, filed February 16, 1932, and assigned to the assignee of this invention which became Patent No. 1,896,764 on February 7, 1933.

25 The operating mechanism comprises in general a U-shaped base or frame 63, a pair of toggle links 65 and 67 for engaging the assembly of the switch members 11, a releasable actuating member 69 for releasably restraining the toggle links 65 and 67 in an operative position, a bifurcated operating lever 71, overcenter springs 73 for connecting the operating lever 71 to the knee of the toggle links, and the operating handle 23. The U-shaped frame 63 is fastened to the insulating base 1 of the circuit breaker by means of four screws 74, two at either end. A pivot pin 77 extends through suitable openings in the U-shaped frame 63 and engages the frame 37 of the central switch member 11. This pin 77 provides a pivot point for the assembly of the switch members 11, all of which are mechanically tied together by the insulating tie-bar 57. Other openings are provided in the base 63 for the reception of the pivot pins 79—one on either side of the U—which provide pivot points for the bifurcated operating lever 71. The lower end of the toggle link 67 is pivotally connected to the frame 37 of the central switch member 11 by the pivot pin 81, the pin 81 serving to connect the operating mechanism 9 and the assembly of the switch members 11. The other end of the toggle link 67 is pivoted at one end of the toggle link 65 by means of the knee pivot pin 83. The knee pivot pin has means associated therewith for engaging one end of each of the overcenter springs 73, one on either end, the other end of the overcenter springs being connected to the operating handle 23.

60 The actuating member 69, which is pivoted about the pin 85, provides a releasable restraining means for holding the toggle links 65—67 in the operable position; the other end of the toggle link 65 being pivotally secured to the actuating member 69 by the pin 89.

65 The movement of the bifurcated operating member 71 is limited by the inwardly extending projections 91 and 93 of the U-shaped frame 63. The projecting end 95 of the actuating member 69 is provided with a latch 97 which is adapted to be engaged by a latch means of the trip device 7 to restrain the actuating member 69 in its normal position.

70 The trip device 7 is entirely assembled on its own base 29 and is completely removable from

the circuit breaker. The trip device includes a thermally responsive trip means indicated generally at 99, and a magnetically responsive trip means indicated generally at 101 for each of the three poles of the breaker. The mechanism of the device is so arranged that a moderate or lower magnitude overload of predetermined duration in the circuit controlled by any one of the poles will actuate the trip mechanism, and a heavier overload or short-circuit condition in the circuit controlled by any one of the poles will actuate the trip mechanism instantaneously to open all three poles of the breaker.

75 Each of the magnetically responsive trip means is mounted on the base 29 by means of a frame 103. The frame 103 is substantially U-shaped, and has an upstanding bracket 105 secured thereto by rivets 107, which bracket functions to support the stationary U-shaped core 109 of the magnetically responsive trip means. Screw fastenings 111 extend through suitable openings in the base 29 and serve to support each of the frames 103. A conductor 113 is provided for each of the trip means and comprises a strip of conducting material, preferably copper, having enlarged end portions which form the terminals 35 and 37 of the trip device. The conductor has a central portion 115 of reduced area, or, which is the same thing, increased resistance, which forms a heat producing portion. The reduced portion is bent backward to form an inverted U-shaped loop about the U-shaped core 109 of the magnetically responsive means. Thus the current flowing in the conductor 113 energizes the magnetically responsive trip means. The U-shaped stationary core 109 is secured to the upstanding brackets 105 by means of a pair of rivets 117, and is thereby positioned between the leg portions of the conductor 113. The core 109 of the magnetically responsive trip means provides the attracting means for the movable armatures 119. Each of the armatures 119 comprises a rectangular strip of magnetic material mounted by means of a guiding member 121 for sliding movement on a pair of cylindrical guide rods 123 which are affixed to the base 29 of the trip device by means of screw fastenings 125. A biasing spring 127 is positioned about each of the guide rods 123, and provides a means for biasing the movable armature 119 away from the stationary core 109. The biasing springs are retained in position on the guide rods by means of washers and cotter pins.

80 It is imperative for accurate operation that the trip device be positioned very accurately with respect to the path of movement of the end 95 of the releasable actuating member 69. In order to accomplish this accurate positioning, there is provided a metallic bracket 129 which is rigidly secured to the central portion of the trip base 29 by means of the central screw fastenings 125. The bracket 129 has a base portion which is of substantially the same outline as the central terminal 35, and is thus adapted to be fastened to the base 1 of the circuit breaker by means of central screw fastenings 41. The central screw fastenings 41 would probably be sufficient to accurately position the trip base with respect to the operating mechanism 9, but in order to insure that the positioning is correct, there is provided an additional positioning means which consists of a projecting male member 131, which extends downwardly through a suitable opening in the central terminal 35 of the trip device, and is adapted to engage a female portion 133 in the

terminal and central shunt 33, this terminal and shunt being securely fastened to the base and accurately positioned with respect to the operating mechanism 9 by means of the screws 135.

5 The bracket 129 has an opening 137 in the upper portion thereof for the reception of a pivoted latch 139, the latch being pivotally mounted in the opening through the agency of a pivot pin 141. The latch 139 is preferably constructed 10 of metal and has a projecting portion 143 for engaging the latch 97 associated with the end 95 of the releasable actuating member 69. A spring 145 is provided for biasing the latch 139 to the latched position, and a notch 147 is provided in the latch for engagement by a bracket 155 attached to the trip bar 149.

15 The trip bar 149 is of molded insulating material and extends across all three poles of the breaker. It is pivotally supported at either end 20 through the engagement of pivot pins 151 with suitable openings in the trip bar itself. The pivot pins 151 are supported by brackets 153 (see Fig. 2) which are fastened to the ends of the trip base by means of screws (not shown).

25 The trip bar 149 engages the latch 139 through the agency of the bracket 155, one end of which engages the notch 147 in the latch 139 and the other end of which is rigidly affixed to the trip bar by a pair of rivets 157. A compression spring 30 159 biases the trip bar in a clockwise direction about its pivot pin to its latched position. Three downwardly extending members 161, one for each pole of the breaker, are affixed to the trip bar by means of rivets, as shown. These downwardly 35 extending members are provided for engaging the armatures 119 of each of the magnetically responsive trip means of the trip device.

40 The end portion 95 of the actuating member 69 includes a bifurcated projection which pivotally supports the latch 97. The latch 97 is biased into the engaged position by a spring 163, and its movement in a clockwise direction is limited by a portion of the bifurcated end of the actuating member 69.

45 Each of the thermally responsive trip means, there being one for each pole of the breaker, comprises a snap-acting bimetal disc 165. The disc 165 is of the type that passes from one to the other of its two oppositely flexed positions 50 with a snap-action when heated or cooled a predetermined amount. The disc 165 is supported by means of an adjusting screw 167. The adjusting screw passes through an opening 169 in one of the legs of the conducting member 113, 55 and is provided with a threaded portion 171 which threadedly engages a threaded opening 173 provided in the opposite leg of the conducting member 113. The disc 165 is provided with a central opening for mounting the same on a groove provided on the forward end of the adjusting screw 167, as best shown in Figs. 3 and 4. The screws 167 pass through openings provided 60 therefor in the cover 30 of the trip device and are provided with knurled operating handles 175 for adjusting the initial position of the disc 165. Each of the discs 165 is thus mounted with its edges in contact with the reduced or heat producing portion 115 of the conductor strips 113, whereby the discs are adapted to be heated by 65 conduction from the conductor 113. The trip bar 149 is provided with a plurality of projections 177, one for each of the snap-acting bimetal discs. The projections 177 are adapted to be engaged and moved by the discs 165 when the 70 discs have been heated a predetermined amount 75

to snap from their initial position to their opposite flexed position. When an overload of moderate magnitude occurs in the circuit in any one of the poles of the breaker and persists for a predetermined period of time, the snap-acting 5 bimetal disc 165 on the pole in which the overload occurs is heated by the heat producing portion of its conducting strip 113. When the disc has been heated a predetermined amount, it snaps to its oppositely flexed position with its 10 edges away from the reduced portion 115 of its conductor strip 113, as shown in Fig. 4. In passing to its oppositely flexed position, the edge of the disc engages the corresponding projection 177 on the trip bar 149 and moves the trip bar 15 in a counterclockwise direction against the bias of the springs 159 to its tripped position to effect release of the pivoted latch 139, resulting in a tripping operation of the breaker. When the disc has snapped to the position shown in Fig. 4 20 in response to a moderate overload, its edges are away from the reduced portion 115 of the conductor strip 113 so that it cools quickly and snaps back to its original or normal position, as shown in Fig. 3.

25 The adjusting screw 167 provides a simple and effective means for adjusting the trip rating of the thermal trip means. Turning the screw 167 in a counter-clockwise direction causes the edges of the bimetal disc 165 to engage the conductor 30 113 with increased pressure, or what is more important, moves the central portion of the disc nearer its dead-center position, so that the disc will be heated the predetermined amount necessary to cause it to snap over to its oppositely 35 flexed position in response to an overload of lower predetermined magnitude, or causes the disc to respond to a moderate overload in a shorter time. When the adjusting screw 167 is turned in a clockwise direction, substantially the reverse 40 action takes place; the contact pressure between the edges of the disc and the conductor strip 113 is reduced, or what is more important, the central portion of the disc is moved further away from the conductor strip so that it requires a 45 greater amount of heat to cause the disc to snap over to its oppositely flexed position. Under these conditions, it requires a greater overload for a given time interval to cause the disc to snap over to effect a tripping operation, or a lower overload 50 for a greater period of time to cause the disc to snap over and effect the tripping operation. It will thus be seen that the particular mounting means of the disc provides a simple and reliable means for adjusting the trip rating of the thermal 55 trip means. If desired, the adjusting screw may be provided with a pointer and the casing 30 of the trip device provided with calibrated indicia representing 80%, 100% and 120% trip load in order to facilitate adjusting of the trip rating of 60 the thermally responsive trip means.

The structural details and operation of the circuit breaker proper and its operating mechanism are fully described in Patent No. 2,047,739, granted H. J. Lingal, on July 14, 1936, and assigned to 65 the assignee of this invention.

The operation of the circuit breaker is briefly as follows: To open the contacts manually, the operating handle 23 is moved clockwise about its pivot 79, whereupon the overcenter springs 73 exert a force having a component tending to move the knee pivot pin 83 of the toggle mechanism toward the base 29 of the trip device or out of toggle. At a certain point, this component of force exerted by the spring 73 becomes sufficient 70 75

to cause the toggle to collapse, resulting in a clockwise movement of the switch members 11 about the pivot pin 77, thus opening the contacts of the breaker. The motion of the central switch member 11 is transmitted to the outer switch members by the insulating tie-bar 57 as has previously been pointed out. The closing operation is substantially the reverse of the opening operation, the knee of the toggle links being moved by the overcenter springs in this case away from the base 23 of the trip device, or in toggle. The combination of the toggle mechanism and the overcenter springs connected to their knee pivot makes it possible to open and close the breaker contacts with a snap-action. The proportions of the moving contact 31 are such that the circuit is first made and finally interrupted through the auxiliary contacts. When the breaker is in the fully closed position, the auxiliary contacts are slightly separated and the circuit is completed through the main contacts.

When the breaker is in the closed circuit position, as shown in Fig. 2, and an overload of moderate magnitude and predetermined duration occurs in the circuit in any one of the poles of the breaker, the heat produced by the reduced portion of the conductor 113 of the pole on which the overload occurs heats the snap-acting bimetallic disc 165 a sufficient amount to cause it to snap to its oppositely flexed position away from the conductor 113, as shown in Fig. 4. The snap-acting movement of the bimetal disc 165 causes the edge thereof to engage the projection 177 of the trip bar 149, and move the trip bar in a counter-clockwise direction to its tripped position, as shown in Fig. 4. The movement of the trip bar 149 to tripped position causes the bracket 155 carried by the trip bar to release the latch 139. The release of the latch 139 allows the actuating member 69 to be moved in a counter-clockwise direction about its pivot pin 85 under the biasing influence of the over-center springs 73. At a predetermined point in the counter-clockwise movement of the actuating member 69, the line of action of the overcenter springs 73 causes collapse of the toggle links 65 and 67 resulting in an opening of the contacts of the breaker in a manner previously described in connection with the manual operation.

The latch 139 returns to latching position under the influence of its biasing spring 145. Due to the fact that the circuits have been opened and that the bimetal disc has snapped to a position away from the reduced portion of the conductor 113, the disc 165 cools quickly and snaps back to its original position with its edges in contact with the conductor 113. The return of the disc 165 to its original position allows the trip bar 149 to be returned to its normal position under the influence of the biasing springs 159, and the bracket 155 reengages the notch 147 in the latch 139. The trip device is thus automatically reset following each tripping operation. To reclose the breaker after a tripping operation, it is necessary to move the operating handle to the full open circuit position. In moving to the full open circuit position a projection 179 carried by the operating member engages and moves the spring biased actuating member 69 to its normal position, during which the latch 97 reengages under the projection 143 of the latch 139. The breaker is now completely reset and may be reclosed by manually moving the operating member 23 to the closed circuit position, during which

the contacts are closed in the manner described in connection with the manual operation of the mechanism.

In the event of a short-circuit or very heavy magnitude overload in the circuit controlled by any one of the poles, sufficient magnetomotive force is supplied by the conducting strip 113 of the circuit in which the overload occurred to cause the armature 119 to be moved to attracted position against the stationary core 109. During the movement of the armature to its attracted position, it engages the downwardly projecting member 161, which is secured to the trip bar, and moves the trip bar in a counterclockwise direction to its tripping position to effect release of the latch 139 and the actuating member 69 in the manner previously described in connection with the tripping operation effected by the thermally responsive trip means.

It will be noted that the conductor strips 113 form the energizing means for both the magnetically responsive trip means and the thermally responsive trip means.

The provision of the improved thermally responsive trip means comprising the snap-acting bimetallic disc and the particular adjusting means provides a simpler, more reliable and more efficient thermal trip means than has heretofore been known or used and the adjusting screw provides a simple means for accurately adjusting the thermal trip rating of the breaker. The disposition of the snap-acting bimetallic disc with its edges in contact with the heat producing portion of the conductor provides for an efficient transfer of heat from the conductor to the thermally responsive trip element, by conduction; and the disc in snapping to its opposite position with its edges away from the heat producing portion of the conductor strip allows the thermally responsive element to cool faster and snap back against the conductor ready for the next operation. Since the disc moves from one to the other of its oppositely flexed positions with a snap-action, it produces a desirable quick and positive movement of the trip bar to tripping position, and a quick return of the thermally responsive element to its normal position.

Although I have shown and described the invention in connection with a particular form of circuit breaker, it is obvious that it is equally applicable to other forms of circuit breaker structures.

While I have shown and described the invention in accordance with the provisions of the patent statutes, it is to be understood that various changes in the structural details thereof may be made without departing from the spirit of the invention. I desire, therefore, that the invention be limited only by the reasonable construction of the appended claims and by the prior art.

I claim as my invention:

1. In a trip device for a circuit breaker, a conductor, and a snap-acting bimetal member mounted with one part in heat conducting relationship to said conductor and said part being movable upon the bimetal member reaching a given temperature to break said heat conducting relationship.

2. In a trip device for a circuit breaker, a conductor, and a snap-acting bimetal mounted with one part only in heat conducting relationship to said conductor, said member when heated a predetermined amount passing from one to the other of two oppositely flexed positions with a snap-

action to effect a tripping operation of the breaker and to move said one part away from said conductor.

3. In a trip device for a circuit breaker, a current-carrying conductor, and a snap-acting thermostatic disc mounted with its edge portions only in contact with said conductor, said disc when heated a predetermined amount changing its position with a snap-action to effect a tripping operation of said breaker and to move its edge portions away from said conductor.

4. In a trip device for a circuit breaker, a current-carrying conductor adapted to be connected in circuit with the contacts of said breaker, and a snap-acting thermostatic disc mounted with only one portion thereof in contact with said conductor, the remaining portions of said disc being disposed away from said conductor, said disc when heated a predetermined amount by said conductor snapping to an inverted position in which all portions thereof are away from said conductor.

5. In a trip device for a circuit breaker, a current-carrying conductor adapted to be connected in circuit with the contacts of said breaker, and a snap-acting thermostatic disc mounted with only its edge portions in contact with said conductor, said disc when heated a predetermined amount snapping to a position with its edges away from said conductor to effect a tripping operation of the breaker.

6. In a trip device for a circuit breaker, a current-carrying conductor, a snap-acting bimetal disc mounted with its edges in contact with said conductor, and means for adjusting the position of said disc to vary the trip rating of said device.

7. In a trip device for a circuit breaker, a current-carrying conductor having a heat producing portion, said conductor being adapted for connection in circuit with the contacts of said breaker, a snap-acting bimetal member, and means mounting said member with only one portion thereof in heat conductive relationship to said heat producing portion of said conductor, the other portions of said bimetal member being disposed away from said conductor, said bimetal member when heated a predetermined amount by the heat produced by said conductor snapping to an inverted position in which all portions thereof are away from said conductor.

8. In a trip device for a circuit breaker, a current-carrying conductor having a heat producing portion, said conductor being adapted for connection in circuit with the contacts of said breaker, a snap-acting bimetallic disc, and means mounting said disc with its edge portion only in contact with said heat producing portion of said conductor, said disc when heated a predetermined amount snapping to an inverted position with its edge portion away from said conductor to effect a tripping operation of said breaker.

9. In a trip device for a circuit breaker, a current-carrying conductor, a snap-acting bimetal disc disposed with its edges in contact with said conductor, and means for varying the contact pressure between the edges of said disc and said conductor to vary the trip rating of the device.

10. In a trip device for a multipole circuit breaker, a trip bar extending across two or more poles of the breaker movable from a normal position to a tripping position to effect a circuit opening operation of the breaker, a plurality of electromagnetic trip means, one for each pole, each operable in response to overloads of pre-

determined values in the circuit of its pole to move the trip bar to tripping position, an energizing conductor for each electromagnetic trip means having a portion of increased resistance, a plurality of snap-acting bimetal discs, one for each pole, mounted with only one portion thereof in heat conducting relationship to the said increased resistance portions of the conductors, each disc when heated a predetermined amount in response to lower magnitude overloads being snapped to an inverted position with all portions thereof away from said conductor to move said trip bar to tripping position.

11. In a circuit breaker provided with relatively movable contacts, a tripping member movable from a normal position to a tripped position to effect opening of said contacts, a conductor adapted to be connected in circuit with said contacts provided with a portion of increased resistance, electromagnetic trip means energized by said conductor operable upon the occurrence of an overload of more than a predetermined magnitude to move said tripping member to tripped position, and a snap-acting bimetal member mounted with only one portion thereof in heat conductive relationship to said increased resistance portion of said conductor, said bimetal member being operable when heated a predetermined amount in response to overloads of lower magnitude to move with a snap action to a position in which all portions thereof are away from said conductor to actuate said tripping member to tripped position.

12. In a circuit breaker, relatively movable contacts, a tripping member movable from a normal position to a tripping position to effect opening of said contacts, a conductor adapted to be connected in circuit with said contacts and having a portion of increased resistance, electromagnetic trip means energized by said conductor operable upon the occurrence of overloads of predetermined magnitude to move said tripping member to tripping position, a snap-acting bimetal disc mounted in heat conductive relationship to the increased resistance portion of said conductor, said disc when heated a predetermined amount in response to an overload of lower predetermined magnitude snapping from one to the other of its two flexed positions to effect movement of said trip member to tripping position, and means movable to adjust the trip characteristic of said bimetal disc.

13. In a circuit breaker having relatively movable contacts, a tripping member movable from a normal position to a tripping position to effect opening of said contacts, a conductor adapted to be connected in circuit with said contacts and having a portion of increased resistance, electromagnetic trip means energized by said conductor operable upon the occurrence of overloads of predetermined magnitude to move said tripping member to tripping position, a snap-acting bimetal member mounted in heat conducting relationship to the increased resistance portion of said conductor, said member when heated a predetermined amount in response to an overload of lower predetermined magnitude snapping from one to the other of its two flexed positions to effect movement of said trip member to tripping position, and means to adjust the normal position of said bimetal member to vary the thermal trip rating of said breaker.

14. In a circuit breaker having relatively movable contacts, a tripping member movable from a normal position to a tripping position to effect

opening of the contacts of the breaker, a conductor adapted to be connected in circuit with said contacts and having a portion of increased resistance, electromagnetic trip means energized by said conductor operable upon the occurrence of overloads of predetermined magnitude to move said tripping member to tripping position, a snap-acting bimetal disc mounted with its edge portions only in contact with the increased resistance portion of said conductor, said disc when heated a predetermined amount in response to lower magnitude overloads snapping to an inverted position in which all portions thereof are away from said conductor to cause movement of said tripping member to tripping position.

15. In a trip device for a circuit breaker having relatively movable contacts, a tripping member movable from a normal position to a tripping position to effect opening of the contacts of the breaker, a conductor adapted to be connected in circuit with said contacts and having a portion of increased resistance, electromagnetic trip means energized by said conductor operable upon the occurrence of overloads of predetermined magnitude to move said tripping member to tripping position, a snap-acting bimetal disc mounted with its edges in contact with the increased resistance portion of said conductor, said disc when heated a predetermined amount in response to lower magnitude overloads snapping from one to the other of its two flexed positions to move said tripping member to tripping position, and adjustable means for varying the contact pressure between the edges of said disc and said conductor to vary the trip rating of said device.

16. In a circuit breaker having relatively movable contacts, operating mechanism for opening and for closing said contacts, and a spring biased actuating member releasable to effect opening of said contacts, the combination of a trip device comprising releasable latch means for restraining said actuating member, a conductor connected in circuit with said contacts, and a snap-acting bimetallic member mounted with its edge portion only in contact with said conductor, said member when heated a predetermined amount being snapped to an inverted position in which all portions thereof are away from said conductor to effect release of said latch means to free said actuating member.

17. In a multiple circuit breaker having a

plurality of pairs of relatively movable contacts forming a plurality of poles, a common operating mechanism for simultaneously opening or closing all of said pairs of contacts, and a spring biased actuating member releasable to effect simultaneous opening of all of said pairs of contacts, the combination of a trip device comprising releasable latch means for restraining said actuating member, a trip bar extending across two or more poles of said breaker biased to a normal position to restrain said latch means in latching position and movable to a tripping position to release said latch means to free said actuating member, a plurality of electromagnetic trip means one for each pole each operable upon the occurrence of overloads of predetermined magnitude in the circuit of its pole to move the trip bar to tripping position, an energizing conductor for each of said electromagnetic means connected in circuit with the contacts of its pole and having a portion of increased resistance, a plurality of snap-acting bimetal discs one for each pole each mounted with only one portion thereof in heat conductive relationship to the increased resistance portions of said conductors, each of said discs when heated a predetermined amount in response to lower magnitude overloads being snapped to an inverted position in which all portions thereof are away from said conductor to cause movement of said trip bar to tripping position.

18. In a circuit breaker, a base, relatively movable contacts, operating mechanism for opening and for closing said contacts, a spring biased actuating member releasable to effect opening of said contacts, a removable trip device comprising a base, a conductor strip secured to the trip base, releasably connectible at each end for mounting the trip base on the breaker base and for providing terminals for the trip device, a releasable latch means for restraining said actuating member, a snap-acting bimetal member mounted with only one portion thereof in heat conductive relationship to said conductor, said bimetal member when heated a predetermined amount by overload current flowing in said conductor snapping to a position in which all portions thereof are away from said conductor to effect release of said latch means to free said actuating member.
